R. J. WOODY

DIAPER, CATAMENIAL BANDAGE, AND THE LIKE

Filed Oct. 22, 1921

Inventor:
Regina J. Wooley
by Frank Wooley
Atty.

UNITED STATES PATENT OFFICE.

REGINA J. WOODY, OF CHESTNUT HILL, MASSACHUSETTS.

DIAPER, CATA MENIAL BANDAGE, AND THE LIKE.

Application filed October 22, 1921. Serial No. 509,638.

To all whom it may concern:

Be it known that I, REGINA J. Woody, a citizen of the United States, and a resident of Chestnut Hill, in the county of Middlesex and State of Massachusetts, have invented a new and useful Improvement in Diapers, Catamenial Bandages, and the like, of which the following is a specification.

My invention relates to diapers, catamenial bandages and the like, either of the sanitary type, so called, intended for a single use, or of the types capable of repeated use.

The primary object of my invention is to provide an article of this class which can be readily fitted to the body of the wearer, whether stout or slender, and securely held in position, without the use of pins. Another object of my invention is to provide such an article which can be manufactured so cheaply as to permit the discarding of the same after a single use. Further objects of my invention are to provide fastening means which are integral with the fabric of which it is made and to provide the article with a centrally arranged reinforcing strip which gives it a double thickness without causing it to bind or sag and thereby produce chafing and discomfort for the wearer.

With these objects in view my invention comprises as its principal feature a fabric sheet which in the case of a sanitary diaper may consist of cotton or absorbent material enclosed in an envelope of gauze, quilted thereto, said sheet being of hour-glass shape, that is to say, being quadrangular and having its ends substantially parallel and its transverse dimension a minimum substantially at its central transverse axis, said sheet having two slots located respectively near the diagonally opposite corners thereof, each slot being arranged to receive the nearer corner of the sheet on the opposite side of its transverse axis so that said sheet may be folded up about the body of the user, and fastening devices which may be cords, secured to or integral with the material of which the article is made. The foregoing and other objects and advantages of my invention will more fully appear from the following detailed description taken in connection with the accompanying drawings and the distinctive features of novelty will be

hereinafter pointed out in the appended claims:

55

In the drawings which accompany and form a part of this specification,—

60

Figure 1 is a plan view of a sanitary diaper, catamenial bandage or the like embodying my invention;

65

Fig. 2 is a plan view showing the same folded with the corners secured together as in use;

65

Fig. 3 is a side view showing the same applied to the body of the wearer;

70

Fig. 4 is a top view of the article folded and having its corners secured in the manner shown in Fig. 2;

75

Fig. 5 is a plan view of a modification showing my invention embodied in an article adapted for repeated use.

80

In the particular drawings selected for more fully disclosing my invention, 10 represents a sheet of fabric, herein shown as cotton or other absorbent material having 75 an envelope of gauze quilted thereto, said sheet preferably being of hour-glass shape, as shown, and provided with two slots 11, 12 located respectively near the diagonally-opposite corners thereof, and, preferably on 80 opposite sides of the longitudinal axis thereof. Attached to each corner of the sheet is a fastening device of any suitable type, and in the present instance said fastening devices are shown as the tying members 13, 14, 85 15, 16. When the fabric sheet consists of cotton or other material enclosed within a gauze envelope, I prefer to make the tying members out of the threads of the gauze envelope by slitting the portion of the gauze 90 which extends beyond the cotton on the transverse axis 17, and then pulling out and twisting together the threads of the portions 18, 19 thereof so as to form the cords, 14, 16 at the adjacent corners of the gauze envelope. It will be understood however that, as in the modification shown in Fig. 5, 95 cords or other tying members may be attached to the corners of the fabric sheet 10.

100

In applying the article to the body of the wearer the sheet is folded on its transverse axis as shown in Fig. 2 and the corners thereof are passed through the slots 11 and 12 which as shown are preferably parallel and inclined to the longitudinal axis of the 105 sheet, and the two pairs of co-operating fas-

tening members 13, 14 and 15, 16 are secured together. Specifically, when the lower half of the sheet is folded over the upper half thereof as shown in Fig. 2, the lower corner 5 20 is doubled over on the rearward portion of the lower half of the sheet and passed through the slot 11, while the other lower corner 21 is folded over the back of the upper portion of the sheet and the two cords 13, 14 10 tied together. The upper corner 22 is then doubled over on the forward portion of the upper half of the sheet and passed through the slot 12 while the corner 23 is folded over the front portion of the lower half of the 15 sheet, and the cords 15, 16 tied together.

It will be obvious that by means of my invention the diaper may be securely fastened about the body of an infant without the use of pins or attaching bands or 20 other supporting members now commonly in use, and that it is self-adjusting, and therefore incapable of sagging and chafing irrespective of the size of the wearer.

If desired a centrally disposed reinforcing 25 strip 24 may be attached by quilting or otherwise to the fabric sheet 10.

As indicated in Fig. 5 my invention may be applied to articles of this class which are intended for repeated use by cutting a sheet 30 10' of suitable fabric along the the transverse axis 25 in the manner indicated in dotted lines and folding the portions 26, 27, 28, 29 over on the sheet as indicated at 26', 27', 28', 29', respectively, and then stitching 35 the triangular portions near the edges thereof to the sheet.

In this manner the sheet is given substantially an hour-glass shape which will permit the same to be applied to the body 40 of the user in the same manner as above set forth in connection with Fig. 1, two slots 11', 12' being cut into said sheet and the corners thereof being provided with fastening members of any suitable type.

45 It will be apparent that my invention may be employed as a bandage for absorbing discharges from the body in the case of venereal and other diseases and also as a catamenial bandage.

50 I am aware that my invention may be embodied in other specific forms without de-

parting from the spirit or essential attributes thereof, and therefore I desire the present embodiments to be considered in all respects as illustrative and not restrictive, reference being had to the appended claims rather than to the foregoing description to indicate the scope of my invention. 55

I claim:—

1. An article of the class described comprising a quadrangular sheet of absorbent material having an envelope of gauze, said sheet and envelope each having its ends substantially parallel and its transverse dimension a minimum substantially at its central transverse axis, and each having two slots located respectively near the diagonally opposite corners thereof, each slot being arranged to receive the nearer corner of the sheet on the opposite side of the transverse axis thereof, and fastening devices secured to the corners of said sheet. 60

2. An article of the class described comprising a sheet of absorbent material having an envelope of gauze, said quadrangular sheet and envelope each having its ends substantially parallel and its transverse dimension a minimum substantially at its central transverse axis, and each having two slots located respectively near the diagonally opposite corners thereof, each slot being arranged to receive the nearer corner of the sheet on the opposite side of the transverse axis thereof, and tying members integral with each corner of said sheet, said tying members consisting of the threads of said envelope of gauze pulled out and twisted together to form cords. 70

3. An article of the class described comprising a fabric provided with two slots located respectively near the diagonally opposite corners thereof, each slot being inclined to its longitudinal axis and arranged to receive the nearer corner of the sheet on the opposite side of the transverse axis thereof, and fastening devices secured to the corners of said sheet. 80

In testimony whereof, I have hereunto subscribed my name this 19th day of October, 1921.

REGINA J. WOODY.
